FISHING REEL

Joseph C. Clark, 4843 Backacher Lane, Orlando, Fla.

Filed May 11, 1960, Ser. No. 60,583

Term of patent 14 years

(Cl. D31—4)

FIG. 1

FIG. 2

FIG. 3

FIG. 4

FIG. 5

FIG. 6

Fig. 1 is a right side elevation of a fishing reel showing my new design.

Fig. 2 is a front elevation thereof.

Fig. 3 is a top plan view thereof.

Fig. 4 is a rear elevation thereof.

Fig. 5 is a left side elevation thereof.

Fig. 6 is a bottom plan view thereof.

The dominant features of my design are shown in full lines.

I claim:

The ornamental design for a fishing reel, as shown and described.
